CLAIM

The ornamental design for recessed furniture riser, as shown and described.

DESCRIPTION

FIG. 1 is a top perspective view of the recessed furniture riser;

FIG. 2 is a top view of the recessed furniture riser of FIG. 1;

FIG. 3 is a side view of the recessed furniture riser of FIG. 1; and,

FIG. 4 is a bottom view of the recessed furniture riser of FIG. 1.

The broken lines show components of the recessed furniture riser that form no part of the claimed design.
